UNITED STATES PATENT OFFICE

2,689,471

RINSING MECHANISM FOR WRINGERS

Orin N. Cooper, Garwin, Iowa

Application June 26, 1951, Serial No. 233,641

13 Claims. (Cl. 68—22)

1

The present invention relates to a rinsing mechanism for wringers.

More specifically, the invention relates to a mechanism that may be embodied into a wringer structure of a washing machine for the purpose of providing rinse water adjacent the wringer rolls at a point where the wash enters or leaves such rolls.

By removing the soap, scum and other foreign matter which clings to clothes before they are passed through a wringer, it is possible to obtain whiter and cleaner clothes particularly by eliminating such foreign matter.

It is one of the objects of the present invention to provide a clothes rinsing structure by supplying rinse water to a hollow pressure release bar thus providing a convenient arrangement for distributing rinse water to the clothes that pass through the wringer.

It is another object of the present invention to provide complementary clothes rinsing mechanism by directing rinse water to a hollowed portion of the drain board structure of the wringer, thus also establishing a rinse from beneath the clothing as the latter garments pass through such wringer.

It is another object of the present invention to provide a suitable means for distributing rinse water to the pressure release bar or drain board of the wringer and to introduce a valving arrangement for cutting off the entire rinsing water or for selectively allowing the rinse water to pass through the pressure release bar or through the drain board of the wringer, depending upon conditions of operation.

It is a further object of the present invention to provide auxiliary manifold arrangements which can be attached to the release bar of the wringer and also to the drain board thereof respectively which may be used as accessory features for supplying rinse water in the path of the clothes that pass through the wringer.

It is a further object of the present invention to provide operable mechanism that is responsive to the bodily movement of the wringer rolls which is directly connected for opening and closing the water supply valve so as to open the valve for the passage of rinse water whenever a piece of clothing enters the wringer rolls. Conversely, the rinse water may be shut off as soon as the rolls come together in their normal contacted positions.

Other objects and advantages relating to the present invention shall hereinafter appear in the following detailed description having ref-

2

erence to the accompanying drawing forming a part of this specification.

In the drawings:

Fig. 1 is a general side elevational view of a conventional washing machine incorporating the rinsing mechanism of the present invention into the wringer structure;

Fig. 2 is a detail traverse cross sectional view of the pressure release bar of the wringer as seen along the line 2—2 in Fig. 1;

Fig. 3 is another transverse cross sectional view of a fragmentary portion of a drain board as seen along the line 3—3 in Fig. 1;

Fig. 4 is a detail side elevational view of a conventional pressure release bar with a manifold rinsing attachment connected therewith to rinse clothing;

Fig. 5 is a detail cross sectional view of the construction illustrated in Fig. 4 and as seen along the line 5—5 therein;

Fig. 6 is a front elevational view of a conventional drain board of a wringer with a manifold rinsing water supply attachment connected therewith;

Fig. 7 is a small fragmentary cross sectional view taken substantially along the line 7—7 in Fig. 6 to show the relationship of the rinsing element to the drain board; and

Fig. 8 is a diagrammatic illustration of a conventional wringer attachment illustrating the use of a valve means for the rinse water which is rendered operative through the relative movement of the wringer rolls.

Fig. 1 shows a conventional washing machine having the tub 1 supported above the operating mechanism compartment 2 with a laterally disposed wringer post 3 terminating in a head 4 that supports a wringer 5 by means of the wringer housing 6 in a conventional manner. The wringer 5 is of the swingable construction that may be limited in any convenient manner as by means of a pin 7 connected with a portion of the wringer post 3 which operates within a limiting shouldered slot 8 that rotates directly with the wringer housing 6.

The wringer 5 is also of a conventional type which includes suitable operative mechanism within the housing 6 that is driven through the interior of the wringer post 3 from operating mechanism confined within the housing 2. The wringer rolls are shown at 9 and 10 arranged to receive the washed clothes from within the washing machine tub 1 over a suitable drain board 11 and beneath the head 12 of

the wringer which is flanked by a pressure release bar 13.

The pressure release bar 13 is usually duplicated on the opposite side of the wringer and the drain board 11 is likewise so duplicated in conventional wringer structures.

A water supply standard or pipe 14 can be secured adjacent the wringer post 3 to receive an external supply of water through a hose such as 15, and water passes through a flexible hose 16 that is connected between the head end 17 of the fixed water supply pipe 14 and a valve structure 18.

The valve structure 18 may be of any suitable type having a main valve 19 that can be opened and closed by means of a valve handle 20. Valve 19 is provided with a manifold extension 21 with valve control outlets 22 and 23 arranged for receiving flexible couplings or hoses such as 24 and 25. The valve manifold 21 may also be provided with a pair of similar valve controlled outlets on the opposite side thereof which are here shown as closed by plugs 26 and 27. By removing plugs 26 and 27, suitable hoses such as 28 and 29 may be also secured to the manifold for supplying a similar pressure release bar such as 13 and an identical drain board such as 11 at the opposite side of the wringer. As shown in Fig. 2, the pressure release bar 13 is hollow to provide an interior duct 30 from which a plurality of drilled openings 31 may be positioned to direct rinse water downwardly upon the clothes and adjacent the wringer rolls 9 and 10. The hose 24 connects by means of a suitable nipple 32 with one end of the pressure release bar 13 to thus conduct rinse water from the water supply system and valve arrangement into the pressure release bar 13.

In Fig. 3, the drain board 11 is provided with a manifold section 33 providing a duct 34 having a plurality of drilled openings 35 connected therewith for directing water upwardly beneath the clothes which pass through the wringer rolls. The hose 25 connects by means of a suitable nipple 36 with the manifold 33 to supply rinse water through the valving system and into the drain board clothes rinsing structure.

With this arrangement, it is possible to provide a rinsing means which is positioned conveniently with respect to the rolls of the wringer and into the most convenient position for access to the clothing that is passed through the wringer. Furthermore, the pressure release bar of the wringer is herein utilized to provide a dual function and the drain board 11 is also so utilized. By having both of the valves 37 and 38 of the manifold open and by opening the main valve 20, rinse water enters the entire system through the hose 15 and passes on to the pressure release bar and drain board for rinsing the clothes above and below respectively. Valves 37 and 38 may be employed to cut off the water to either one of the units comprising the pressure release bar 13 or the drain board 11.

Figs. 4 and 5 show a manifold attachment 39 secured by suitable straps such as 40 and 41 to a pressure release bar 13a and rinse water is brought through a flexible hose 24a from the valve arrangement 18 as in the preferred construction. The manifold 39 has an interior duct 30a and a plurality of water supply openings 31a leading therefrom.

Figs. 6 and 7 illustrate the use of a relatively flat manifold 42 secured at 43 and 44 to the surface of the drain board 11a and water is sup-

plied to this manifold 42 through a flexible hose 25a that is also connected with the valving system.

In the rinsing arrangement illustrated in Fig. 1, and in Figs. 4 and 6 respectively, the use of flexible hoses such as 24-24a and 25-25a will permit the free operation of the pressure release bar respectively and will also establish a means for connecting a rinse system with a drain board which may be movably mounted with respect to the wringer. Furthermore, the use of a flexible coupling such as 16 will permit swinging of the wringer 5 without interfering with the supply water system.

In Fig. 8, one end of the wringer 5 is diagrammatically illustrated showing the interior thereof and the relatively movable wringer rolls 9 and 10. Roll 9 is movably guided by means of a bearing block 59 between suitable guides such as 51 and 52, while the wringer roll 10 is usually fixed by means of a bearing block 53 secured in place between guides 51 and 52.

This construction utilizes a similar valving arrangement 18a as in the Fig. 1 construction having a manifold 19a which can be opened and closed by an operating lever 20a. Water is supplied through a flexible hose or coupling 16a to the valve 19a for entry into a manifold 21a. However, the valve 19a is opened by means of the relative movement of the wringer rolls so that the rinse water is normally shut off until a piece of clothing enters between the rolls to separate such rolls as 9 and 10, whereupon the rinse water will automatically be supplied to the pressure release bar structure or to the drain board structure. This is accomplished by the use of a cable in the form of a flexible wire such as 54 which passes through a suitable thimble 55 secured to one of the vertical guide members 51 and is secured to any one of the movable portions of the movable roll 9 such as to the bearing 59 where the cable is attached at 56. The other end 57 of the cable may be attached in any one of a number of positions in the openings 58 in the lever 20a. A tension spring 59 normally maintains the lever 20a in a position to close the valve 19a, and a pull on the cable 54 responsive to the bodily movement of the wringer roll 9 will open the valve 19a to supply rinse water to the structures hereinbefore described. It should also be noted that the lever 20a may be operated by hand since the slack in the cable will permit such action. Considerable saving of water can be automatically accomplished through the use of a wringer and rinsing structure substantially as illustrated in Fig. 8.

While the foregoing description has been directed to preferred embodiments of the invention, it is to be understood that certain changes may be made in the details of construction, combination and arrangement of parts, and that such changes are contemplated without departing from the spirit and scope of the invention as claimed.

For example, pipe 14 and hose 16 can be suitably installed within the post 3 and wringer base to connect with a valve 18 mounted for use within the wringer head 6 with only the stems of the valves 20, 37 and 38 extending outwardly of the head for convenient use by the operator. Hose 70 couplings such as 24 and 25 may likewise be concealed within the wringer head for connection with the release bar 13 and drain board 11 if so desired.

What I claim is:

1. In a wringer, wringer rolls, a pressure re-

lease bar carried adjacent one side of said wringer rolls, and rinse means to direct rinse water against clothes entering said wringer rolls comprising perforated conduit means connected with said pressure release bar and having a water entry inlet connected to receive supply water for discharge through the perforations of said conduit means, and a water supply means connected with said water entry inlet of said conduit means, said conduit means perforations being arranged to discharge rinse water in the direction of the clothes entering said wringer rolls.

2. In a wringer, wringer rolls, a drain board supported adjacent said rolls and therebelow, and rinse means to direct rinse water against clothes entering said wringer rolls in supporting contact with said drain board comprising perforated conduit means connected with a drain surface portion of said drain board and having a water entry inlet connected to receive supply water for discharge through the perforations of said conduit means, and a water supply means connected with said water entry inlet of said conduit means, said conduit means perforations being arranged to discharge rinse water away from the drain surface portion of said board and in the direction of the clothes entering said wringer rolls over and in contact with said drain board.

3. A rinsing means for a wringer having wringer rolls, a pressure release bar carried adjacent said rolls and at one side of said wringer, and a drain board supported adjacent said wringer rolls and therebelow, said rinsing means consisting of said pressure release bar provided with a hollow water conducting section positioned over the clothes receiving portion of said wringer rolls and having perforations communicating with said hollow section to direct rinse water downwardly upon clothes entering said wringer rolls, and said drain board being provided with a hollow water conducting section positioned below the clothes receiving portion of said wringer rolls and having perforations communicating with said hollow section of said drain board to direct rinse water upwardly and against the under portions of the clothes entering said wringer rolls.

4. A rinsing means for a wringer having wringer rolls, a pressure release bar carried adjacent said rolls and at one side of said wringer, and a drain board supported adjacent said wringer rolls and therebelow, said rinsing means consisting of said pressure release bar provided with a hollow water conducting section positioned over the clothes receiving portion of said wringer rolls and having perforations communicating with said hollow section to direct rinse water downwardly upon clothes entering said wringer rolls, and said drain board being provided with a hollow water conducting section positioned below the clothes receiving portion of said wringer rolls and having perforations communicating with said hollow section of said drain board to direct rinse water upwardly and against the under portions of the clothes entering said wringer rolls, and water supply means connected with said release bar and said drain board respectively and having communication with said hollow water conducting sections of each to supply rinse water for the clothes rinsing operation of each.

5. A rinsing means for a wringer having wringer rolls, a pressure release bar carried adjacent said rolls and at one side of said wringer,

and a drain board supported adjacent said wringer rolls and therebelow, said rinsing means consisting of said pressure release bar provided with a hollow water conducting section positioned over the clothes receiving portion of said wringer rolls and having perforations communicating with said hollow section to direct rinse water downwardly upon clothes entering said wringer rolls, and said drain board being provided with a hollow water conducting section positioned below the clothes receiving portion of said wringer rolls and having perforations communicating with said hollow section of said drain board to direct rinse water upwardly and against the under portions of the clothes entering said wringer rolls, and water supply means connected with said release bar and said drain board respectively and having communication with said hollow water conducting sections of each to supply rinse water for the clothes rinsing operation of each, said water supply means comprising a water flow control valve means carried by said wringer, a water supply line to said valve means, and flexible conduits interposed between said valve means and the hollow water conducting sections of the pressure release bar and the drain board respectively.

6. A rinsing means for a wringer having wringer rolls, a pressure release bar supported for limited movement relative to the wringer and disposed adjacent said rolls and at one side of said wringer, and a drain board supported for limited movement adjacent said wringer rolls and therebelow, said rinsing means consisting of said pressure release bar provided with a hollow water conducting section positioned over the clothes receiving portion of said wringer rolls and having perforations communicating with said hollow section to direct rinse water downwardly upon clothes entering said wringer rolls, and said drain board being provided with a hollow water conducting section positioned below the clothes receiving portion of said wringer rolls and having perforations communicating with said hollow section to direct rinse water upwardly and against the under portions of the clothes entering said wringer rolls, and water supply means connected with said release bar and said drain board respectively and having communication with said hollow water conducting sections of each to supply rinse water for the clothes rinsing operation of each, said water supply means comprising a control valve fixedly mounted upon said wringer, a water line to said valve, and flexible water delivery conduits connected with said valve and with said pressure release bar and said drain board respectively for communication with the hollow water conducting sections of each.

7. A rinsing means for a wringer having wringer rolls, a pressure release bar carried adjacent said rolls and at one side of said wringer, and a drain board supported adjacent said wringer rolls and therebelow, said rinsing means consisting of said pressure release bar provided with a hollow water conducting section positioned over the clothes receiving portion of said wringer rolls and having perforations communicating with said hollow section to direct rinse water downwardly upon clothes entering said wringer rolls, and said drain board being provided with a hollow water conducting section positioned below the clothes receiving portion of said wringer rolls and having perforations communicating with said hollow section of said drain board to direct rinse water up-

wardly and against the under portions of the clothes entering said wringer rolls, and water supply means connected with said release bar and said drain board respectively and having communication with said hollow water conducting sections of each to supply rinse water for the clothes rinsing operation of each, said water supply means comprising a valve mechanism, a water supply line connected with said valve mechanism, water discharge conduits connected between said valve mechanism and said pressure release bar and said drain board respectively for communication with the hollow water conducting sections of each, and said valve mechanism including selective control valves to supply rinse water to the bar and/or the drain board and to regulate the volume of flow of water delivered through said supply line.

8. In a wringer having clothes wringing rolls and a pressure release bar for separating said rolls carried by said wringer adjacent the rolls and above the path of the clothes entering said rolls, the combination of fluid conduit means connected with said pressure release bar and having perforations therein arranged to direct rinse fluid in a predetermined direction upon clothes passing through said wringer, and a fluid supply means connected with said fluid conduit means to deliver rinsing fluid to said conduit means.

9. In a wringer having clothes wringing rolls and a drain board supported adjacent the rolls and therebelow, the combination of a fluid conduit means carried by said drain board and disposed adjacent a fluid draining surface portion thereof, said conduit means having fluid discharge openings formed therethrough and arranged to direct rinse water fluid away from said fluid draining surface portion of the board and against the underside of clothes passing through said wringer rolls, and a fluid supply means connected with said fluid conduit means to deliver rinsing fluid to said conduit means.

10. In a wringer having relatively bodily movable wringer rolls, a pressure release bar for the manual release of said rolls, and a drain board beneath said rolls, the combination of a clothes rinsing means consisting of perforated conduit means for said pressure release bar to direct rinse fluid upon clothes passing through said wringer rolls, perforated conduit means for said drain board to direct rinse fluid against the underside of the clothes passing through said wringer rolls, rinse fluid supply means connected with said conduit means to supply rinsing fluid thereto, a valve unit for said fluid supply means to interrupt the

flow of rinsing fluid, and operative mechanism connected with said valve unit and with at least one of said wringer rolls and arranged to close said valve unit upon bodily separation of said wringer rolls.

5 11. A clothes rinsing mechanism for a clothes wringer comprising, in combination, bodily separable wringer rolls, rinse conduits carried adjacent said rolls and providing means to direct rinsing fluid against clothing passing through said wringer rolls, a fluid supply system connected with said rinse conduits, a valve in said system to control the flow of fluid to said conduits, and operative means to open and close said valve, said operative means having a connection with said wringer rolls rendered responsive to the bodily separation of said wringer rolls to shut off said valve and the rinse fluid supply to said rinse conduits upon roll separation.

10 12. In a pressure release bar for a wringer having bodily separable wringer rolls actuated by said bar with said bar positioned adjacent said rolls and above the path of clothes passing through said rolls, the improvement in said bar consisting of providing a hollow section in the bar over the path of clothes passing to the wringer rolls together with apertures leading from said hollow section and opening in the direction of said passing clothes, and fluid conducting means connected with said bar and having communication with the hollow section thereof to supply fluid to said bar for rinsing clothes through the apertures in said bar.

15 13. In a drain board for a wringer having clothes wringing rolls disposed above the board and wherein clothes are passed through said rolls and over said drain board, the improvement in said board consisting of providing a hollow section in said board disposed across the path of travel of the clothes to the rolls and therebeneath together with apertures leading from said hollow section and opening in the direction of said passing clothes, and fluid conducting means connected with said board and having communication with the hollow section thereof to supply fluid to said board for rinsing clothes through the apertures in said board.
